UNITED STATES PATENT OFFICE.

RUDOLF ZOPPA, OF MONTCLAIR, NEW JERSEY.

ELECTRIC CUT-OFF FOR MARINE AND OTHER STEAM-ENGINES.

1,056,482.

Specification of Letters Patent. Patented Mar. 18, 1913.

Application filed December 30, 1912. Serial No. 739,303.

To all whom it may concern:

Be it known that I, RUDOLF ZOPPA, a citizen of the German Empire, residing in Montclair, county of Essex, and State of New Jersey, have invented certain new and useful Improvements in Electric Cut-Offs for Marine and other Steam-Engines, of which the following is a specification.

This invention relates to an electric cut-off for marine and stationary steam-engines by which the supply of steam to the engine can be automatically cut off and the engine stopped either when the screw of a marine engine is lifted out of the water or when in case of an accident, the stopping of a stationary engine is required from any part of a factory, so that the marine or stationary steam-engine is more fully within control, less exposed to shocks when the screw leaves the water, and also the engine quietly stopped in case of emergency for preventing accidents to life and limb, and for this purpose the invention consists of a cut off for steam-engines which comprises a throttle-valve for the steam supply-pipe, a valve-rod, a stop-plate on the valve-rod guided and movable with the same, a fulcrumed armature; two pairs of electro-magnets actuating said armature, stop-links pivoted at their inner ends to a fixed plate and near their outer ends to lever-arms of said armature, and a switch-device for exciting one electromagnet or the other for oscillating the armature and stop-links for automatically closing or opening the throttle-valve and supply or shut off the steam to the engine.

In the accompanying drawings, Figure 1 represents a sectional side-elevation of my improved electric cut-off for marine or stationary engines, showing the throttle-valve in open position, Fig. 2 shows a switch-device located near the screw of a vessel, and electrically connected with the cut-off, Fig. 3 is also a sectional side-elevation of the cut-off showing the throttle-valve in closed position, Fig. 4 is a front-elevation of the cut-off device, and Fig. 5 is a horizontal section on line 5, 5, Fig. 4.

Similar letters of reference indicate corresponding parts throughout the several figures of the drawings.

Referring to the drawings, *a* represents the main steam supply-pipe of a marine, stationary or other steam-engine. In the supply-pipe is located the usual throttle-valve *c* which is guided in a valve-casing *b*. Above the valve is arranged a valve-seat *c*¹, while a stuffing-box *c*² for the valve-rod *c*³ is arranged at the lower portion of the valve-casing. The valve-rod *c*³ is connected at its lower end with a slide-plate *e*, which is guided in suitable ways of an upright supporting-plate *e*¹. On the supporting-plate *e*¹ are mounted brackets *e*⁴ which carry two parallel rods *e*³ on which is guided by bracket-sleeves *e*⁵ a vertically reciprocating face-plate *e*² which is connected by a rod *e*⁶ with a strap on an eccentric of the driving shaft or with any other reciprocating portion of the engine so that a corresponding vertically-reciprocating motion is imparted to the face-plate *e*². To the face-plate *e*² is fulcrumed a rocking armature-lever *d* which carries at its outwardly-projecting tapering end two armatures *d*¹, which work in connection with two pairs of electromagnets *d*², which are supported by angle-brackets *d*³ on the face-plate *e*², as shown clearly in Fig. 4. The face-plate *e*² is provided with a slot *s* in which the armature-lever *d* is oscillated, and with a web or plate *s*¹ at right angles thereto, to which the armature-lever *d* is fulcrumed. The inner end of the armature-lever *d* is formed of two obtusely-angled arms *d*⁴ which are provided with recesses *d*⁵ at their outer ends that engage pins *d*⁶ on two links *f*, which are pivoted to the web *s*¹ at their inner ends, as shown clearly in Figs. 1 and 3. One of the pivot-links *f* extends in upward, the other in downward direction so as to be placed into the path of the raised upper or lower portions *e*⁷ of the slide-plate *e*. The raised portions *e*⁷ are provided with elastic cushions *e*⁸ for taking up the concussions with the ends of the pivot-links *f* when either one of them is placed in contact therewith. The electromagnets *d*² are placed in electrical connection with a switch-device when the cut-off device is used with a marine-engine on board of a vessel, said switch-device consisting of a float *h*, which rises up and down with the level of the water in a well *h*¹.

passing through the hull of the vessel, the float h being provided with a stem h^2 which is guided by rollers h^3 in the well and provided with a projection h^4 that engages a fulcrumed switch-lever h^5 , the opposite end of which forms electrical contact with two stop-plates h^6 , one above and the other below the inner end of the fulcrumed lever, as shown in Fig. 2.

10 When the throttle-valve b is in its open position, the lower electro-magnet is energized and the lower armature of the lever d is in contact with the lower stop-plate h^6 , so that the lower pivot-link actuated by the 15 lower arm of the armature-lever d^1 is placed in the path of the vertically-reciprocating slide-plate and the lower valve or stop on the same, as shown in Fig. 1. In this position of the armature-lever d , the slide-plate 20 e is prevented from being raised as the end of the lower pivot-link f is located in its path so that the throttle-valve is held in open position and prevented from closing the steam supply-pipe a by the throttle- 25 valve c . As soon as the propeller of the vessel is raised above the level of the water, the float h sinks in the well h^1 to such an extent that the projection h^4 on the stem of the same will engage the switch-lever h^5 30 and move its end into contact with the upper contact-stop, so that instantly the lower electromagnet d^2 is switched out and the upper electromagnet d^2 is switched into circuit, thereby the upper armature of the lever 35 d^1 attracted, and the lower pivot-link f moved out of the path of the slide-plate e , while on the other hand the upper pivot-link f is moved inwardly into the path of the upper stop of the slide-plate e so as to 40 engage the same and move the slide-plate e and thereby the throttle-valve b into closed position in the steam-supply-pipe a , as shown in Fig. 3. As soon as the propeller is returned below the level of the water, the 45 float rises and the position of the switch-lever is reversed, that is to say, moved into its former position so that the upper electromagnet d^2 is switched out and the lower electro-magnet d^2 switched into circuit and 50 the armature-lever with the lower pivot-link moved into the position shown in Fig. 1, so as to open the throttle-valve of the steam supply-pipe by the downward motion imparted to the slide-plate e of the lower pivot-link f placed into its path.

When the improved cut-off is used for stationary engines in mills, factories and the like, a number of ordinary push-button switches are arranged in different parts of 60 the building within convenient reach of the machines that are driven by the stationary steam-engine, so that whenever, in case of an accident to any machine or attendant, it is desired to quickly stop the motion of

the engine, the simple actuation of the 65 switch will close the throttle-valve in the manner described and stop the engine by cutting off the supply of steam to the same. Likewise a number of switches may be arranged on board of a vessel, so that in case 70 of an accident, such as the bursting of a steam-pipe or breaking of an engine-cylinder, the throttle-valve could be closed and the motion of the engine arrested.

I claim:

1. An electric cut-off for marine and other steam-engines, comprising a throttle-valve, a slide-plate provided with stops, a valve-rod connecting the throttle-valve with said slide-plate, a reciprocating face-plate, an 80 armature-lever, fulcrumed to said face-plate, electro-magnets on said face-plate for oscillating said armature-lever and pivot-links operated by said armature-lever for engaging either one of the stops of the slide-plate 85 and moving the throttle-valve into open or closed position.

2. An electric cut-off for marine and other steam-engines, comprising a throttle-valve in the steam supply-pipe, a valve-rod, a 90 slide-plate provided with stops connected with said valve-rod, a reciprocating face-plate, pivot-links on said face-plate and adapted to engage one or the other stop of the slide-plate, a forked armature-lever fulcrumed to said face-plate, and engaging said pivot-links, electromagnets arranged at opposite sides of the armature-lever, and a switch adapted to throw one electromagnet or the other into circuit for oscillating 95 the armature-lever and links and closing or opening the throttle-valves.

3. In an electric cut-off for marine and other steam-engines, the combination of a stationary main-plate, a slide-plate guided 105 on the same, a throttle-valve in the steam supply-pipe, a valve-rod connecting the throttle-valve with the slide-plate, stops on the slide-plate, a reciprocating face-plate guided on the supporting plate, two pairs 110 of electromagnets, an armature-lever provided with obtusely-angled arms, pivot-links engaged by said arms and a switch-device for throwing one electromagnet or the other into circuit and move either one of the pivot-links into the path of the slide-plate for 115 moving the throttle-valve into open or closed position.

4. In an electric cut-off for marine and other steam-engines, the combination of a 120 stationary main-plate, a slide-plate guided on the same, a throttle-valve in the steam supply-pipe, a valve-rod connecting the throttle-valve with the slide-plate, stops on the slide-plate, a reciprocating face-plate 125 guided on the main-plate, pivot-links applied to the face-plate and provided with pins, two pairs of electromagnets, an armature-lever

provided with obtusely-angled and recessed arms for engaging pins on the pivot-links, and a switch-device actuating alternately the electromagnets and oscillating the armature-lever and pivot-links for placing the throttle-valve into open or closed position in

In testimony, that I claim the foregoing as my invention, I have signed my name in presence of two subscribing witnesses.

RUDOLF ZOPPA.
